Patented Oct. 14, 1919.

UNITED STATES PATENT OFFICE.

RAYMOND Q. BROWN, OF KANSAS CITY, MISSOURI.

ELECTROLYTIC CELL.

1,318,724.

Specification of Letters Patent.

Patented Oct. 14, 1919.

Application filed February 21, 1917. Serial No. 150,600.

To all whom it may concern:

Be it known that I, RAYMOND Q. BROWN, a citizen of the United States, residing at Kansas City, in the county of Jackson and 5 State of Missouri, have invented certain new and useful Improvements in Electrolytic Cells, of which the following is a specification.

This invention relates to electrolytic cells 10 of that character commonly used for liberating oxygen and hydrogen from water, and my object is to produce a cell of this character which is efficient in operation and of simple, strong, durable and inexpensive construction, and which furthermore automatically indicates the volume of water in the 15 cell and guards against danger of mixing the gases in the event the water falls below a predetermined level.

With the objects named in view the invention 20 consists in certain novel and useful features of construction and combinations of parts as hereinafter described and claimed; and in order that it may be fully understood reference is to be had to the accompanying drawing, in which:

Figure 1, is a top plan view of an electrolytic cell embodying my invention.

Fig. 2, is an edge elevation of the cell.

30 Fig. 3, is a horizontal section taken on the line III—III of Fig. 2, but on a larger scale.

Fig. 4, is an enlarged vertical section taken on the line IV—IV of Fig. 1.

Fig. 5, is a section taken on the line V—V 35 of Fig. 1.

In the said drawing 1 is the shell which is deep and wide but narrow, and said shell preferably tapers downwardly as shown in Fig. 2.

40 The shell is provided at its upper end with an outwardly projecting annular flange 2, and said flange is provided with a pair of notches 3, through which extend bolts 4 provided with angular head 5, fitting against 45 the underside of flanges 2 and the outer side of the shell and rigidly secured to the same in any suitable manner. The bolts 4, are adapted to have clamped upon them the ends of conducting bars of an adjacent cell, not 50 shown, as forming no part of this invention.

55 6 is the cover plate for the shell, the same being secured in position by bolts 7 which extend up through said cover plate and the flange 2 and are engaged by clamping nuts 8.

To insulate the shell from the cover plate,

a gasket 9 is interposed between said parts, and to insulate the bolts 7 from the cover plate 6, the latter is provided with openings 10 in which fit insulation disks 11, similar but larger disks 12 being mounted on the bolts between the cover plate 6 and the washers 13 fitting around the bolts and clamped against disks 12. By this arrangement the cover is secured firmly in position 65 without being in direct contact with the shell.

Depending from the cover plate within the shell and of substantially the same cross sectional configuration as the latter, is 70 a bell 14, and pendent from said bell is a sack or diaphragm 15 which is of such material that it is impervious to gas but not to water. The sack or diaphragm acts to prevent oxygen liberated within the sack 75 and hydrogen liberated exteriorly from mixing, one of such gases being collected in the bell 14 and the other in the shell around the bell, it being understood that the water level should be maintained about the lower 80 end of the bell to utilize the latter as a partition between the two charges of gases above the water level.

A float 16 is arranged within the shell to indicate the level of the water therein. Any 85 suitable type of float may be employed, that shown having a vertical stem 17 extending slidably through a guide bracket 18 and the cover and into a transparent tube 19 projecting upward from the cover and secured to the same with a gas tight relation. The location of the upper end of the rod 17 within the tube 19 will indicate the level of 90 the water in the shell.

Arranged vertically within the bell and 95 sack is a thin flat anode 20, the same being suitably secured rigidly to the enlarged lower ends of a pair of inverted bolts 21, said bolts extending upward through insulation disks 22 fitting in openings in the cover, and 100 through insulation disks 23 and 24, respectively interposed between the headed ends of the bolts 21 and the cover, and between the latter and nuts 25 screwed on the bolts to secure the same in rigid relation to the 105 cover. From one of the bolts 21 an electric wire, not shown, will lead in the customary manner, and a second wire, not shown, will be connected as customary to one of the bolts 4, electrically connected to the shell 110 which constitutes the cathode of the cell.

As a reliable protection against the pos-

sibility of mixture of gases, vent tubes 26 and 27 extend through and are insulated from the cover, the said tubes being secured in position by nuts 28 with their lower ends 5 between the water level and the lower end of the bell, so as to be prepared to permit gas to escape without mixing, in the event the water level should fall below the lower ends of both vent tubes. Either of the vent 10 tubes is adapted for use as a filling tube.

The generation process is the same with this cell as with others of its type, that is to say the gases which are produced by electrolysis within and without the sack, adjacent 15 the anode and cathode respectively, pass up into the bell and shell above the water line and from thence through a pipe 29 from the bell and a pipe 30 from the shell into storage tanks or the like, not shown. The advantage 20 derived through the large surface of the anode and cathode is common to electrolytic cells of this class, and the electric current in effecting decomposition of the water of course passes through the sack interposed 25 between the anode and cathode as usual. I have however obtained better results by causing the side walls of the shell to converge downwardly, as by disposing the walls closer to the anode at the lower end of the 30 cell, the resistance to the passage of the current diminishes correspondingly and thus it is believed, a wider distribution of the current is effected and a greater quantity of gases liberated in proportion than could be 35 accomplished with a cell having parallel instead of converging sides.

Secured to the lower end of the anode 20 is a spacing sleeve 21 of insulating material, the same effectively guarding against 40 physical contact between the anode and the inclosing sack 15. It is of course desirable

to guard against contact between the sack and the anode to avoid injury to the former and the possibility of hydrogen passing up through the sack and into the bell. 45

From the above description it will be apparent that I have produced an electrolytic cell embodying all of the features enumerated as desirable, and while I have illustrated and described what I now believe 50 to be the preferred type, I wish it to be understood that I reserve the right to make all changes which properly fall within the spirit and scope of the appended claim. 55

I claim:

An electrolytic cell comprising a receptacle constituting a cathode provided at its upper end with outwardly projecting flanges, a covering bolted upon and insulated from the flanged end of the cathode, 60 and provided with a bell depending into the cathode, a sack attached at its upper or open end to and depending from the bell within and out of contact with the cathode, a float for indicating the water level within 65 the cathode, a pair of independent gas vent tubes extending down through the covering into the cathode within and without the bell and terminating short of the lower end of the latter and insulated from the covering, 70 a plate constituting an anode and disposed within the bell and sack out of contact with both, and provided with a pair of headed bolt extensions extending up through and insulated from and clamped to the covering, 75 and a pair of bolts having angular heads secured to and against the outer side of the cathode and against the underside of one of the flanges thereof, and spaced from and projecting upwardly beyond the covering. 80

In testimony whereof I affix my signature.
RAYMOND Q. BROWN.
